RECEPTACLE

Nicholas P. Courtney, Passaic, N. J.

Application March 17, 1932, Serial No. 599,397

3 Claims. (Cl. 220—43)

This invention relates to receptacles, and aims to provide certain improvements therein.

Although the invention may be utilized in conjunction with several types of receptacles, it is described and illustrated herein as adapted to that type of receptacle known as friction top cans, which comprise essentially a top or cover designed to be pressed into the upper end of the can, the parts being so constructed that the cover is held in position by frictional contact with a can. Such cans require a prying instrument of some sort to remove the cover. In Patent No. 1,826,740 granted to me I have described and claimed a construction in which a rigid prying implement is provided which is normally connected with the peripheral bead of the can cover, so as to be capable of sliding around the latter while at the same time being operable to pry off the cover by application of the leverage of the implement at the different points to which it may be slid. The invention set forth in said patent is very effective in its operation, but its application to the can cover ordinarily involves a machine operation in bending at least one of the hinging elements around the cover bead so as to produce a stable connection. This construction has the advantage that the unit is assembled before shipping and is always at hand during use of the can.

According to the present invention I provide an opener of this general type wherein the advantages of assembly at the packing plant are availed of, and in which the opener may be always at hand in use, but wherein the construction of the opener itself is considerably simplified and its assembly with the can requires no machine operation. To this end I provide an opener having a means for detachable connection with the can which may be operated by hand and in which the connection is sufficiently secure to insure that the can reaches the customer with the opener connected therewith and also to permit the customer to reattach it to the can when only part of the contents of the latter are used. In the preferred construction of my invention the opener is adapted to engage a part of the can in an inoperative position so as to require no change in the construction of the can top or its cover. The preferred form of the invention includes certain other features of improvement which will be hereinafter more fully pointed out.

In the drawing, wherein I have shown a preferred form of the invention,—

Figure 1 is a top view of a can showing an

opener attached thereto, according to my invention.

Fig. 2 is an elevation of the can of Fig. 1.

Fig. 3 is a detailed sectional view on the line 3—3 of Fig. 1.

Referring to the drawing, let A indicate a can of suitable construction, as shown in detail in Fig. 3, wherein the can top is formed with a U-shaped annular groove E while the cover F is formed with a similar U-shaped projection F' designed to fit in the groove. A form of implement or opener which I provide in connection with cans of this type is shown in perspective in Fig. 2 and in detail in Fig. 3. It comprises a flat bar of metal G which is bent to form a suitable prying portion H designed to fit under the peripheral bead of the can cover, as indicated in broken lines in Fig. 3, and by using the upper bead of the can as a fulcrum the cover is easily pried from its closed position, the tool being capable of being inserted at various points under the cover bead. As a means for temporary and removable connection of the opener to the can A, I have formed the opposite end of the opener with a fairly large hook-shaped portion N at one end which provides a recess capable of extending over the upper can bead O, and also the outer edge of the can cover, the hook end being received in the recess P of the can cover. An effective detachable connection may be afforded by striking down a tongue Q from the body of the tool, which tongue is adapted to bear against the bead O, the parts being so proportioned that there is a close frictional or other contact designed to maintain the tool in attached position until intentionally removed.

It will be observed that the construction shown is characterized by a detachable connection of the tool with the can, and in said construction it is not necessary to use any machine or hand tool to produce the connection. Assembly is hence much facilitated and the cost of a complete unit of can and attached prying tool is considerably cheapened. At the same time the invention has considerable advantages over any attempts which have been made in the past to provide some means whereby an opening tool of any description could be associated with a can before shipment so that the ultimate purchaser would have some certainty of receiving the opener with the can. In certain instances opening tools of one description or another have been banded to the can by paper labels or otherwise, but these did not provide for security in assembly, nor for the possibility of reattach-

ment. The present invention provides for direct assembly before shipping, and means for reattachment during use by the consumer.

While I have shown and described a preferred form of the invention, it will be understood that I do not wish to be limited thereto, since various changes may be made therein without departing from the spirit of the invention.

What I claim is:

- 10 1. The combination with a friction top can of an opener therefor adapted to pry the cover from the can, the can being formed with a groove in its top and the cover being formed with a similar groove, and the opener being provided with a hook-shaped end adapted to engage the periphery of the cover and the top of the can body for detachably connecting the opener to the can, the hook-shaped end having resilient means assisting in such connection.

2. The combination with a friction top can of an opener therefor adapted to pry the cover from the can, the can being formed with a groove in its top and the cover being formed with a similar groove, and the opener being provided with a hook-shaped end adapted to engage the periphery of the cover and the top of the can body for detachably connecting the opener to the can, the said hook-shaped end having a spring portion engaging one of said parts and assisting in such connection.

3. The combination with a friction top receptacle of a lever adapted to pry the cover therefrom, and means for releasably attaching the lever to the receptacle, said means comprising a bent portion of the lever adapted to engage with it the periphery of the cover and the body of the receptacle.

NICHOLAS P. COURTNEY.
